UNITED STATES PATENT OFFICE

90,922

DESIGN FOR AN ARTICLE OF FOOD

Fred E. Miller, Mangum, Okla.

Application July 19, 1933. Serial No. 48,756

Term of patent 7 years

To all whom it may concern:

Be it known that I, FRED E. MILLER, a citizen of the United States, residing at Mangum, in the county of Greer and State of Oklahoma, have invented a new, original, and ornamental Design for an Article of Food, of which the following is a specification, reference being had to the accompanying drawing, forming part thereof.

I claim:—

The ornamental design for an article of food as shown.

FRED E. MILLER.
